MECHANICAL PENCIL OR THE LIKE

Yukio Horie, Tokyo, Japan, assignor to Dai Nihon Bungu Kabushiki Kaisha (also trading as the Japan Stationery Co., Ltd.), Tokyo, Japan, a corporate body of Japan

Filed Oct. 18, 1968, Ser. No. 14,056

Claims priority, application Japan Apr. 24, 1968

Term of patent 14 years

Int. Cl. D19—06

U.S. Cl. D74—24

FIG. 2 FIG. 3

FIG. 1

FIG. 4

FIG. 5

FIG. 1 is a perspective view of a mechanical pencil showing my new design as it appears with the tubular tip protector in its extended position by the clockwise rotation of the checkered portion;

FIG. 2 is an elevational view thereof;

FIG. 3 is another elevational view thereof as it appears with the tubular tip protector in its retracted position by the counterclockwise rotation of the checkered portion;

FIG. 4 is a top plan view thereof; and

FIG. 5 is a bottom plan view thereof.

I claim:

The ornamental design for a mechanical pencil or the like, as shown and described.
